PELT STRETCHER

Raymond D. Philbrick, Ericson, Nebr.

Application July 6, 1939, Serial No. 233,071

7 Claims. (Cl. 149—21)

My invention relates to new and useful improvements in pelt stretchers.

An important object of my invention is to provide a pelt stretcher that will efficiently stretch and dry the fresh pelts of killed animals.

Another object of my invention is to provide a pelt stretcher that is adjustable in its nature to accommodate varying sizes of pelts.

Still another object of my invention is to provide a pelt stretcher that is unique in its construction to permit the pelts to be easily drawn thereon or removed therefrom and that will permit both sides of the pelt to be exposed to a free circulation of air to assure a rapid and efficient drying of the pelt.

Yet another object of my invention is to provide a pelt stretcher that is simple in construction and that will permit the pelt to be removed without danger of being twisted or otherwise unduly distorted.

Yet another object of my invention is the provision of a pelt stretcher that is durable in its construction and is efficient and efficacious in the performance of its duties.

Other objects and advantages of my invention will be apparent during the course of the following description.

In the drawing, forming a part of this specification, and in which like numerals are employed to designate like parts throughout the same,

Figure 1 is a top plan view of a device embodying my invention, and illustrating a pelt in association therewith,

Figure 2 is an enlarged fragmentary view of the same, illustrating one of the pelt engaging hooks,

Figure 3 is a vertical sectional view taken on the line 3—3 of Figure 2, and

Figure 4 is a fragmentary perspective view, illustrating the means for locking the stretching arms in the desired position.

In the accompanying drawing, wherein for the purpose of illustration, is shown a preferred embodiment of my invention, the numerals 10 and 11 designate stretcher arms pivotally connected, as at 12, and with the upper portions 13 and 14 thereof arcuately bent or bowed to substantially conform to the shape of a pelt 15. The arms 10 and 11 are substantially rectangular in cross section and are constructed from any suitable metallic bar that is sufficiently rigid or nonresilient to resist the contraction of the pelt in drying. When the pelt has been properly removed from the animal it will be substantially in the shape of a sack and with the fur on the

inside. The pelt may then be easily drawn over the stretching arms, as illustrated in Figure 1, and the hooks 16 and 17 attached to the free ends thereof.

The hooks 16 and 17 are normally positioned 5 intermediate the free ends of the arms and are of substantially elongated U-shaped formation to prevent the pelt from being accidentally disengaged therefrom. The shank portions 18 of the hooks are looped around the stretcher arms as 10 at 19 and the ends 20 thereof are bent angularly outwardly therefrom toward the free end of the stretcher arms and have their extremities hooked, as at 21, to frictionally engage or receive the outer edge of the said stretcher arms 15 and at a point spaced substantially from the looped portions 19. As clearly illustrated in Figure 3, the loop portions 19 are not tightly wrapped around the stretcher arm but are fashioned with the loop of substantially greater 20 length than the width of the bar to leave a space, as at 22, to permit a free sliding movement of the hooks relative to the bar and to enable the said hooks to be pivotally actuated with respect thereto.

The end 23 of the rod 24 is received in the aperture 25 at the free end of the stretcher arm 10 and with the extremity 26 thereof wrapped around the end 23 to securely hold the same against accidental displacement. The rod 24 30 extends transversely of the longitudinal axis of the stretcher bars and is fashioned into a depending loop formation 27. The end portion 28 of the rod extends beyond the loop formation 27 at substantially right angles to the main portion of the rod and the extremity 29 thereof is bent angularly thereto in a direction away from and parallel to the rod to terminate in a looped formation 30.

The end 31 of the transversely extending rod 40 32 is looped through the aperture 33 adjacent the free end of the stretcher arm 11 and the extremity 34 thereof is looped around the end 31 to hold the said rod against displacement. The rod 32 extends in spaced parallelism with the rod 24 and is slidably received by the depending looped portion 27. The extremity 35 is looped around the rod 24, as at 36, and in a manner to permit the same to be easily slidable with respect thereto. The end 37 of the locking 50 link 38 is pivotally attached to the looped extremity 30 of the rod 24, and the end 39 thereof is loosely wrapped around the end 31 of the rod 32.

The free ends of the stretcher arms 10 and 11

11 may be pivotally actuated toward each other or away from each other and the rods 24 and 32 are slidably interlocking to permit a free movement of the arms within reasonable limits. When 5 the raw pelt 15 has been drawn on the stretcher rods, the free ends of the rods are pivoted toward each other to permit the hooks 16 and 17 to be attached to the pelt. The end 40 of the back side of the pelt is drawn underneath the 10 shank 13 of the hook 16 and wrapped around the hook to permit the pointed end 41 thereof to pierce the same. The belly or underside of the pelt 42 is similarly attached to the hook 17 and, when the free ends of the stretcher arms 15 are spread apart, the ends of the pelt will be positioned at substantially the middle of the elongated hooks. The ends of the hooks extend a substantial distance beyond the point where the hooks penetrate the pelt to obviate the possibility 20 of their becoming disengaged from the pelt should the same be dropped or handled in a rough or careless manner.

Because of the interlocking engagement of the extremities 21 of the hooks with the stretcher 25 arms, they may be pivoted relative thereto in a direction away from the pivoted end thereof, as illustrated in Figure 2, but any application of force that attempts to move the hooks toward the pivoted end of the arms, such as the force 30 effected by the contraction of the drying pelt, will be resisted by reason of the locking engagement of the extremities 21 with the outer edges of the stretching arms.

When the free ends of the stretching arms 35 have been spread a sufficient distance apart to tautly stretch the fresh pelt, the end 29 of the locking link 38 may be slidably actuated along the end 31 of the bar 32 and into binding relation therewith in a manner to prevent sliding 40 motion of the rods 24 and 32 relative to each other. The link 38 will lockingly engage the rod 32 until the link is manually released and positioned substantially parallel to the portion 28 of the rod 24 to permit free sliding movement of the rods with respect to each other.

It may thus be seen that, as the pelt dries, the rigid or nonresilient construction of the stretcher arms will resist the contracting stresses 50 of the pelts and that the locking link 38 will prevent the free ends of the arms from being moved toward each other. The locking engagement of the extremities of the hooks will prevent the pelt from crawling along the stretcher arms toward the pivoted ends. When the pelt is held 55 in the tautly stretched condition hereinbefore described, the air will have access to the fur side of the pelt and thereby assure a rapid and efficient drying of the same.

It is to be understood that the form of my 60 invention, herewith shown and described, is to be taken as a preferred example of the same, and that various changes in the size, shape and arrangement of parts may be resorted to without departing from the spirit of my invention, or the 65 scope of the appended claims.

Having thus described my invention, I claim:

1. A pelt stretcher comprising a pair of pivoted stretching members adapted to be manually spread apart to stretch a pelt mounted thereon, 70 and hooks adapted to engage the pelt substantially intermediate the free ends of the said stretching members, said hooks having their shank portions loosely looped around the stretching members for free sliding movement 75 therealong, the extremities of the said loops ex-

tending angularly outwardly toward the free ends of the stretching members and hooked over the outer edge thereof to prevent movement of the said hooks toward the pivoted end of the stretcher, the said hooked ends readily disengaging from the members to permit pivotal movement of the hooks in a direction away from the pivoted end of the members. 5

2. A pelt stretcher comprising a pair of pivoted stretching members adapted to be manually spread apart to stretch a pelt mounted thereon, 10 hooks adapted to engage the pelt substantially intermediate the free ends of the said members, said hooks having their shank portions loosely looped around the stretching members for free sliding movement therealong, the extremities of the said loops extending angularly outwardly toward the free ends of the stretching members and hooked over the outer edge thereof 15 to prevent movement of the said hooks toward the pivoted end of the stretcher but in a manner permitting the hooks to be pivotally moved away from the said pivoted ends of the members, and means to lock the stretching members in the extended position. 20

3. In a pelt stretcher, a pair of pivotally connected stretching bars having the pivoted ends thereof bowed to form a substantially V-shaped frame, a hook slidably mounted on each of the stretching bars, said hooks being positioned intermediate the stretching bars and with the shank portions thereof loosely looped around the bars for free sliding movement therealong, the extremities of the said loops extending toward the free ends of the stretcher bars and terminating in hooked ends adapted to frictionally engage the outer edges of the bars at a point spaced from the looped portion to prevent actuation of the hooks toward the pivoted end of the stretcher but permitting free actuation thereof 30 in a direction away therefrom. 35

4. In a pelt stretcher, a pair of pivotally connected stretching bars having one of their ends bowed to form a substantially V-shaped frame, 45 a transverse rod mounted at the free end of one of said arms and formed with a depending loop portion the end of which extends at right angles to the arm and with the extremity thereof being bent angularly outwardly and fashioned into a loop formation, a transverse rod mounted at the free end of the other of the said arms and slidably received in the depending loop portion of the first-mentioned rod and with the extremity thereof looped around the said rod, and a link 50 rod having one end pivotally attached to the looped extremity of the first-mentioned rod and with the other end thereof looped around the second-mentioned rod, said link rod adapted to bindingly engage the second-mentioned rod to prevent the actuation of the free ends of the stretching bars toward each other. 55

5. In a pelt stretcher, a pair of pivotally connected stretching bars having one of their ends bowed to form a substantially V-shaped frame, a hook slidably mounted on each of the stretching bars, said hooks being positioned intermediate the stretching bars and with the shank portions thereof looped around the bar and extending toward the free end thereof and terminating in a hooked end adapted to frictionally engage the outer edge of the bar at a point spaced from the looped portion to prevent actuation of the hook 70 toward the pivoted end of the stretcher but permitting free actuation thereof in a direction away therefrom, a transverse rod mounted at the 75

- free end of one of said arms and formed with a depending loop portion the end of which extends at right angles to the arm and with the extremity thereof being bent angularly outwardly and fashioned into a loop formation, a transverse rod mounted at the free end of the other of the said arms and slidably received in the depending loop portion of the first-mentioned rod and with the extremity thereof looped around the said rod, and a link rod having one end pivotally attached to the looped extremity of the first-mentioned rod and with the other end thereof looped around the second-mentioned rod, said link rod adapted to bindingly engage the second-mentioned rod to prevent the actuation of the free ends of the stretching bars toward each other.
6. In a pelt stretcher, a pair of pivotally connected stretching bars having one of their ends bowed to form a substantially V-shaped frame, hook means slidably mounted on the stretching bars, a transverse rod mounted at the free end of one of said arms and formed with a depending loop portion the end of which extends at right angles to the arm and with the extremity thereof being bent angularly outwardly and

fashioned into a loop formation, a transverse rod mounted at the free end of the other of the said arms and slidably received in the depending loop portion of the first-mentioned rod and with the extremity thereof looped around the said rod, and a link rod having one end pivotally attached to the looped extremity of the first-mentioned rod and with the other end thereof looped around the second-mentioned rod, said link rod adapted to bindingly engage the second-mentioned rod to prevent the actuation of the free ends of the stretching bars toward each other.

7. In a pelt stretcher, a pair of pivotally connected stretching bars, means to hold the bars in an expanded position comprising an arm carried by one of the bars, an arm carried by the other of the bars, said arms being connected for mutual sliding movement relative to each other, said first arm having an extending end portion, and a locking member slidable on the said second arm and cooperative with the extending end of the first arm to effect a binding engagement therebetween and to prevent relative sliding movement of the said arms.
